RAILWAY BRAKE GEAR STRUCTURE

Thomas C. Soddy, Chicago, Ill., assignor to Chicago Railway Equipment Company, Chicago, Ill., a corporation of Illinois

Filed Apr. 29, 1957, Ser. No. 655,785

5 Claims. (Cl. 188—219.1)

The invention relates to railway brake gear and more particularly to a brake beam and associated parts, in which the beam main member consists of a single elongated member extending substantially from end to end of the beam and mounting separately formed end members through which the beam is supported from adjacent truck structure and by which thrust is applied to brake shoes engaging the truck wheels.

A familiar type of brake beam is of the truss type consisting of a main tension member and a main compression member extending from end to end of the beam, said members being spaced apart a substantial distance intermediate their ends and converging toward the ends, and there secured together and mounting a brake head or similar end member. The brake head or end member mounted on the beam has a body part forming a pocket receiving the adjacent ends of the compression and tension members, the inner forward and rear walls of the pocket diverging inboard of the beam to accommodate the converging end portions of the truss members. If such a head were mounted upon the end of a single member beam, there would be a substantial space between the inner forward and rear walls of the beam pocket and the only thrust exerted on the beam by the end member would be at the extreme outer face of the head.

The main object of the present invention is to adapt a single member beam for tight assembly with an end member which is also adapted to fit tightly on the end of the truss type beam. By thus making possible the use of the same end member on beams of both types, the stock required for maintenance shops on a railroad will be cut in half, and it will not be necessary to select two groups of heads for replacement assemblies.

Another object is to utilize an individual brake lever as a safety support and guide for a beam of the single main member type.

In the accompanying drawings illustrating selected embodiments of the invention:

Figure 1 is a side elevation of a portion of a railway truck showing brake gear embodying a single main member beam and the support thereon on the truck frame and the brake operating mechanism.

Figure 2 is a detail horizontal section through the end portion of the beam shown in Figure 1, with a brake shoe removed. The section is taken on line 2—2 of Figure 1.

Figure 3 is a detail vertical section on line 3—3 of Figure 2.

Figure 4 is a section corresponding to Figure 2, but taken through the left hand end of the brake beam, and showing another form of end member.

Figure 5 is a side elevation of the structure shown in Figure 4.

In the structure shown in Figures 1, 2 and 3, the truck frame 11 is supported from a wheel 13 in the usual manner and includes a tubular cross member 15 extending from side to side of the truck. Paralleling and adjacent to member 15 is a brake beam main member 17 consisting of a channel having an upright web 19, and upper

2

and lower horizontal flanges 21. An end member comprising a brake head 23 is applied to each end of beam 17 and includes a body portion having a pocket opening inboard of the beam and receiving the end of channel 17.

5 The head includes a recess 25 for a rectangular hanger 27 by which the beam is suspended from a bracket 29 carried on the truck frame. A brake shoe 31 is seated upon elements 23a of the brake head and opposes the wheel tread. The brake mechanism includes an individual fluid pressure cylinder 33, associated with each end of the beam and carried upon a bracket 35 on truck frame 11, and a brake lever 36 pivoted on a truck frame bracket 37 and actuated by the rod 39 of a piston in cylinder 33. Lever 36 has an enlarged shoulder 38 directly engaging the 10 rear face of the beam to thrust the brake shoe against the wheel.

A horizontal projection 40 on the lower end of lever 36 extends under brake beam member 17 and forms a horizontal shelf adapted to engage the lower flange 21 of the beam if it tilts or if hanger 27 fails. The shelf therefore serves normally as a guide to prevent brake head 23 tilting, so that only one end of the shoe rides on the wheel, and also serves as a safety device to avoid the beam falling to the rail.

15 25 The pocket in the brake head receiving the end of the beam main member is substantially deeper from front to rear than the main member, in order to receive the end portion of the tension member of a truss type beam. In the absence of such a tension member, there is provided 30 a filler block 41 which seats against the inner face of upright web 19 and against the inner face 43 of the forward wall of the pocket in the brake head. This filler block extends inboard of the beam beyond the inboard side of the brake head and provides for the direct transmission of 35 thrust from lever 36 diagonally of the beam to the forward wall of the brake head and thence to the brake shoe. A lip 45 on the outer end of block 41 definitely positions the block lengthwise of the beam for the assembling operation, when rivet 47 is driven through the 40 beam diagonally with its heads seated against the rear face of boss 49 on the brake head and the forward face of a flange 51 on the brake head. The rivet is disposed at the angle indicated so that on a truss type beam it will be normal to the beam tension member, as clearly shown 45 in Patent 2,587,915, issued March 4, 1952.

Accordingly, the head used on the familiar truss type beam, shown in the above mentioned patent, is readily applicable to the single main member beam illustrated in the accompanying drawings, and the thrust applied by 50 lever 36 to beam member 17 will be transferred in a direct line to the brake shoe and wheel.

Figures 4 and 5 illustrate another type of beam end, in which the main beam member 67 is received in the pocket of an end member 69 which mounts a brake head 71 and extends outboard of the head and there forms a tang 72 whereby the beam is supported from a bracket 73 on an adjacent truck frame 75. The end member is shown with a flange 77 extending inboard of the brake head and riveted at 79 to member 67. A filler 81 is positioned between channel upright web 69 and the rearward face of the forward wall 83 in the end member pocket and the thrust from brake lever 85 is transmitted from the rear face of the end member through filler block 81 to the forward wall of the end member and by the 60 latter direct to the rear face of the brake head. The end member is secured to the brake beam by a diagonal rivet 87. The brake head is secured to the end member by rivets 89 extending through webs 91 normal to the face of the head and corresponding webs 93 projecting upwardly and downwardly from the body of end member 69.

Both forms of the invention illustrated make possible the use of a single design of brake head on a truss type

beam or on a single main member type of beam, of either the hanger type, or the hangerless type, the brake thrust being transmitted directly from levers engaging the rear face of the beam through the beam web, the filler block, the end member and the brake shoe. In the first form of the invention, the end member is the brake head. In the second form of the invention, the end member mounts the head, which in turn mounts the shoe, not shown.

The above description and the accompanying drawings are illustrative, and it will be understood that the details of the structure may be varied substantially without departing from the spirit of the invention as expressed in the claims.

What is claimed is:

1. A railway brake beam comprising a single elongated main member extending substantially from end to end of the beam and having an upright web, a separately-formed end member at each end of the beam which is adapted to mount a brake shoe and through which end member the beam is supported, each end member forming a pocket having a front wall and a rear wall spaced apart, said pocket receiving the end of the main member between said walls and said rear wall being seated against the rear face of said web, and a filler block seated against the front face of the rear wall of the beam main member and against the opposing rear face of said end member front wall, said filler block forming a part for transmitting thrust directly from said beam main member to the brake shoe mounting elements of said end member.

2. A railway brake beam according to claim 1 in which the end member front wall is inclined inwardly and forwardly from the end of the beam, the filler block forming a wedge between said faces, and the outboard end of the filler block has a lip engaging the end of the main member and holding the block against movement inboard of the end member.

3. A railway brake beam according to claim 1 in which the elongated main member is a channel with an upright web and vertically spaced flanges, at least partly received in the end member pocket, and the filler block lies between said channel flanges and bears throughout its rear face against the inner face of said channel web and

throughout a portion only of its forward face against the forward wall of the end member pocket.

4. In combination, a railway brake beam comprising an elongated main member, a brake head mounted on each end of said member and including a through passageway receiving and surrounding transversely the end portion of said main member and including a brake shoe mounting portion, the portion of the head forming the forward wall of said passageway opposing said main member but being spaced therefrom and diverging therefrom inwardly from the end of the beam, there being a flange projecting outboard from the side of the shoe mounting portion of the head and having a forward face substantially parallel to said forward wall, a filler block between said member and said forward wall and having a lug engaging the outer end of said member and having a rear surface in contact with said member and having an inclined forward surface in contact with said forward wall, and a rivet extending through said member, filler block and head flange with its axis disposed at right angle to said forward wall and said flange face, and a brake gear lever engaging the rear face of the beam main member inboard of said filler block and brake head and thrusting the beam and head forwardly.

5. The combination of a brake beam and lever according to claim 4 in which the lever includes a projection underlying a portion of the beam and forming a safety support for the beam.
